United States Patent Office.

JOHN S. PERRY, OF ALBANY, NEW YORK, ASSIGNOR TO JOHN S. PERRY,
TRUSTEE AND EXECUTOR, AND NATHAN B. PERRY, OF SAME PLACE.

Letters Patent No. 79,594, dated July 7, 1868.

IMPROVEMENT IN BASE-BURNING STOVES.

The Schedule referred to in these Letters Patent and making part of the same.

TO ALL WHOM IT MAY CONCERN:

Be it known that I, JOHN S. PERRY, of Albany, in the county of Albany, and State of New York, have invented certain new and useful Improvements in Base-Burning Stoves; and I do hereby declare that the following is a full, clear, and exact description thereof, reference being had to the accompanying drawings, making a part of this specification, in which—

Figure 1 is a front elevation of my improved stove.

Figure 2 is a diametrical section through the stove, taken in the plane indicated by red lines $z z$ in figs. 1 and 3.

Figure 3 is a view of the upper portion of the stove, as seen by removing the top plate thereof.

Figures 4 and 5 are modifications, intended to show a mode of exposing a portion of the bottom of the oven-chamber.

Similar letters of reference indicate corresponding parts in the several figures.

This invention relates to certain improvements on that class of stoves which are provided with magazines for supplying coal to fire-pots arranged beneath them, and which have their coal-supplying magazines so applied within external casings as to form straight flues or chambers, which allow the products of combustion to be carried to the tops of the stoves.

The invention which I have made in such stoves consists mainly in projecting the back flue beyond the body of the outer casing which surrounds the coal-magazine, so as to form a laterally-enlarged chamber, which will allow of any required amount of draught, and, in a stove of a given size, will allow of an increased capacity of coal-magazine, and admit of a comparatively narrow flue-space surrounding the said magazine, as will be hereinafter explained.

The invention also consists in constructing such a stove with an oven-chamber in its upper portion, having an opening through its bottom leading to the coal-magazine, for supplying the same with coal, and having its side or sides, and a portion of its bottom, exposed to the heated products of combustion on their way to the projecting chamber at the back of the stove, as will be hereinafter explained.

It further consists in constructing the side wall of an oven, which is arranged over the magazine of a base-burner having a lateral enlargement or flue projecting beyond the external case, with openings and with a damper, for the purpose of allowing, when desired, a portion of the heated products to pass through and across the oven on their way to the escape-flue, as will be hereinafter explained.

To enable others skilled in the art to understand my invention, I will describe its construction and operation.

In the accompanying drawings, A represents the base-section of the stove, which serves, in conjunction with the section M, to enclose and form the ash-pit. The section M is supported upon and secured to the base A, and provided with doors, B, which allow access to the fire-pot C and its grate b, and also to the ash-pit. The fire-pot C is constructed so as to flare upward, and it is supported at its upper end by means of a flange resting upon suitable projections extending inward from the upper contracted end of the section M. This fire-pot C may be provided with a lining, a, and is provided with a grate, b, which latter rests upon a cross-bar, b', and is allowed to oscillate freely. A ring, g, which is suitably perforated, is arranged upon the flange of the fire-pot, or upon the ring which supports the same, and is adapted to serve as a register for regulating the supply of air to the combustion-chamber above said pot, said air entering the stove through register-openings c, made through doors B, leading into the space below the fire-pot, as shown in fig. 2.

The conical section G, which is supported upon the contracted upper end of the section M, is perforated in a suitable manner, and provided with illuminating-windows, E, and an illuminating-door or doors, E', for exposing the light of the fire. The door E' allows access to the fire-pot, for starting a fire and for any other purpose.

Within the contracted upper end of the illuminating-section G, stirrups or concave-chairs, e, are formed, at

equal distances apart, for receiving lugs d , which are cast upon the upper enlarged portion of the inverted conical base D, and serving as means for sustaining this base in a central position over the fire-pot, as shown in fig. 2. This inverted conical base D forms the lower end of the cylindrical coal-magazine H, and receives upon it this cylinder H, thereby supporting the latter in proper position within the cylindrical casing I, and leaving an ascending-flue space or chamber, f, between said cylinders, as shown.

The casing I is secured to and supported upon the upper contracted end of the illuminating-section G, and receives upon its upper end the flaring ring J, which forms the top section of the stove, and which is provided with a central hole through its cap, closed, when desired, by a removable cover, K.

The upper end of the magazine H terminates at the base of wall P, and is covered by means of a horizontal plate, which forms the bottom of an oven, S, which oven is surrounded by an annular flaring wall, P.

An opening is made through the bottom plate of the oven S, which is provided with a sliding valve, j, having a rod, j^3 , projecting from it, and extending through the front part of the section J. Said opening is designed for allowing access to the magazine, for supplying it with coal.

In fig. 2, the wall P is represented with scores or openings through its upper end, for the purpose of allowing some of the heated products of combustion to pass through the oven on their way to the escape-flue f^2 .

By reference to figs. 2 and 3, it will be seen that a chamber, N, is formed at the back of the cylindrical casing I, which extends beyond the line of the body of this casing, and forms an enlarged flue, or an enlargement of the flue partially surrounding the magazine H.

This enlargement forms a flue, f^1 , which extends from the top of the illuminating-section G to the top plate of the section J, and which is separated from the vertical flue f by means of divisions p p' and horizontal deflecting-plates S' , which latter direct the rising products of combustion forward, and thus arrest their passage from vertical flue f into the extended chamber N. The escape-flue f^2 is applied to the chamber N, near its lower end.

It will be seen that the products of combustion will rise directly from the fire-chamber, or space enclosed by the illuminating-section G, into the flue f , and pass into the space f^3 surrounding the oven S, thence pass backward into the chamber f^1 , and finally escape through the flue f^2 .

In figs. 4 and 5 it will be seen that provision is made for allowing the rising products of combustion to impinge against a portion of the bottom of the oven S. This is effected by reducing the diameter of the coal-magazine at its upper end, so as to form a central pipe-connection, H', which may be closed by a hinged damper, j^1 , moved by a rod, j^2 , or other analogous device.

In these figures I have also shown a sliding damper, r' , applied to perforations made through the front part of the oven-wall P, so that portions of the escaping products of combustion may be conducted through the oven S, or not, as circumstances require. In all other respects the parts shown in figs. 4 and 5 may be constructed and arranged as described for similar parts shown in figs. 1, 2, and 3.

It will be seen from the above description that, as there is no limit to the size of the projecting chamber N, any desired amount of draught can be provided for. I am enabled to make the upward flue, f , of any required width, and I am enabled to increase the size and capacity of the magazine laterally without enlarging the outer casing. In stoves having the downward or discharge-flue contained within the body of the casing of the magazine, in order to secure sufficient capacity for this flue, it was necessary to make the upward flue too wide. By making it narrow, the heat impinges more sharply against the sheet-iron casing, and consequently more heat is radiated. This necessity of making the flue very wide, of course reduced the size of the magazine.

I have represented in the accompanying drawings, and above described, a stove which is constructed so that the products of combustion ascend directly from the fire-chamber to the top of the flue-chamber surrounding the coal-magazine; but my invention is applicable to stoves which are so constructed that the products of combustion descend, after leaving the fire-pot, before they ascend to the top of the stove. I do not, therefore, confine my invention to a direct-flue stove; nor do I desire to claim broadly a stove having a jacket or casing surrounding the coal-magazine. The chamber N', which I have shown, is for the purpose of enlarging the escape-flue, and not for the purpose of forming an outer casing to the magazine.

Having described my invention, what I claim as new, and desire to secure by Letters Patent, is—

1. In a base-burning magazine-stove, wherein the products of combustion are carried directly upward from the fire-pot, the flue-chamber N, extending partly around and beyond the body of the casing I, substantially as described.
2. The laterally-projecting flue-chamber N, constructed with side divisions p p' , bottom division p , and deflecting-plates s' , and applied to a stove which is constructed upon the principle herein described.
3. An elevated oven, S, applied on top of the coal-magazine H, in combination with a flue-chamber, N, which projects beyond the body of the casing I, substantially as described.
4. Providing for exposing the outer portion of the bottom of the elevated oven S to the heated products of combustion, in combination with an extended flue-chamber, N, and in a stove constructed substantially as described.
5. Providing an oven, S, with a register, I, and opening r , when employed in combination with an extended flue-chamber, N, arranged as described.
